UNITED STATES PATENT OFFICE.

EMIL GREWEY, OF YONKERS, NEW YORK.

DESIGN FOR A BADGE OR SIMILAR ARTICLE.

SPECIFICATION forming part of Design No. 28,339, dated March 8, 1898.

Application filed January 17, 1898. Serial No. 666,997. Term of patent 14 years.

To all whom it may concern:

Be it known that I, EMIL GREWEY, a citizen of the United States, residing at Yonkers, in the county of Westchester and State of New York, have invented and produced a new and original Design for a Badge or Similar Article; and I do hereby declare the following to be a full, clear, and exact description of the same, reference being had to the accompanying drawing, forming a part thereof.

In the accompanying drawing the figure is a plan view of a badge or similar article embodying my design.

As shown in the drawing, the leading or material feature of my design consists of a wreath of flowers partially inclosing a compass-like ornamentation having radiating points, the compass being in the background, upon and within the compass a Maltese cross having upon it a shield bearing a coat of arms, the shield being surrounded by a scroll, and above the shield a shoulder-piece of armor, and on top of the armor a globe surmounted by a cross.

A represents a panel in the four corners of which appear triangular panels *a*, upon which panels may be represented any suitable letters or configurations. A wreath *B*, composed of laurels or other suitable flowers tied with a flowing ribbon *c*, partially surrounds a compass-like ornamentation *E*, which latter appears in the background. The points

e of the compass-like ornamentation fall within the wreath *B* and are arranged concentrically of the main panel. On the compass 35 appears a Maltese cross *G*, within which is arranged a shield *H*, and on the shield or escutcheon any suitable lettering may be represented. On the shield is represented a coat of arms consisting of an anchor *I*, crossed diagonally by a dagger *K*, and extending vertically across the anchor and dagger appears a battle-ax *L*, passing through a bundle of sticks. On top of the shield appears a shoulder-piece of armor *M*, comprising a helmet 40 and vizor, and on top of the armor is represented a globe *N*, having a horizontal band *n* and a vertical band *n'*, surmounted by a cross *n²*. On the Maltese cross and inclosing the shield appears a heraldic scroll *O*, having a 45 panel *o* for the insertion of any desired inscription.

Having now described my invention, what I claim as new, and desire to secure by Letters Patent, is—

The design for a badge or similar article, substantially as herein shown and described.

In testimony whereof I hereunto affix my signature in presence of two witnesses.

EMIL GREWEY.
